United States Patent Office.

JOEL HAYDEN, JR., OF HAYDENVILLE, MASSACHUSETTS.

Design No. 3,335, dated January 12, 1869.

DESIGN FOR A WATER-CLOSET RECEIVER.

The Schedule referred to in these Letters Patent and making part of the same.

To all whom it may concern:

Be it known that I, JOEL HAYDEN, Jr., of Haydenville, Hampshire county, State of Massachusetts, have invented a new and improved Design for Water-Closet Receivers; and I do hereby declare that the following is a full and clear description thereof, reference being had to the accompanying drawings, forming part of this specification.

In the drawings—

Figure 1 is a side view, and

Figure 2, a plan view of my design.

The object of my design is to render the receiver of a water-closet compact and convenient, and of a form adapted to its peculiar requirements, with the least possible waste of stock; and by setting forth these requirements as they are met, my design can best be described.

The whole shell is to be cast at once, and for this purpose it is necessary that the shape should admit of successful coring. This is easily accomplished, the entrance and exit-holes being large and opposite to each other.

The general shape of the receiver is an irregular semi-ovate shell, with a large circular hole in the sectional plane, and a smaller one near the apex, the latter forming the bottom, and communicating with the sink-pipe, and the sectional plane forming the top.

A line, drawn through the centres of both holes, would form an eccentric axis to the shell, the bulge forming the rear part of the receiver, and giving room for the pan when dumped.

Around the lower hole, extending downward, is a short tube, or neck, which has a flange, extending out

from its outside surface, and forming a base for the receiver, and this is intended to be screwed down to the floor, the tube projecting through, and communicating with the sink-pipe.

The flange is circular for about three-fourths of its circumference, but extends backward, in a T-shaped projection, which is braced to the bulge by an upright plate, and further supports the receiver.

The top entrance-hole is circumscribed with a rim, which has three projections from its inner edge, extending toward the centre, and serving to keep the porcelain dish in place when set in.

The left rear portion of the shell is carried out to a rectangular corner, which extends in depth about two inches, and has at its extreme corner a screw-hole, for the valve to be screwed into.

At the left rear side of the shell, nearly opposite to the rear edge of the entrance-hole, is a small hole, through which the hinge-rod is inserted in setting the hinge, and along this top left edge the shell is chambered, for the working-space of the valve-lever, which passes over the hinge-rod.

A projection from the side of the shell, in front of the small hole, forms a stop for the lever operating the pan.

Having described my invention,

What I claim as new in design, and desire to secure by Letters Patent, is—

The design for water-closet receivers herein set forth.

J. HAYDEN, JR.
